UNITED STATES PATENT OFFICE

2,206,736

CONNECTOR DEVICE

Samuel Sutter, Philadelphia, Pa., assignor to
 Hugh H. Eby, Inc., a corporation of Pennsylvania

Application December 16, 1936, Serial No. 116,188

8 Claims. (Cl. 173—328)

5 My invention relates to connector devices and, more particularly, to sockets of the multi-contact variety, especially adapted to receive the prongs of a vacuum tube or the like for the purpose of supplying potentials to the various elements thereof.

10 Connector devices of the type to which my invention pertains heretofore have been provided with a plurality of circumferentially located axially extending openings affording passageways for the separate wires of a multi-conductor cable. Such construction necessitates the separate insertion of each conductor into the opening provided therefor, before the bare ends of the 15 cable are soldered to their respective female contact elements.

It is, accordingly, an object of my invention to provide a connector device of the type referred to that shall be simplified in construction and shall permit expeditious assembly with a plurality of contact elements and a multi-wire cable.

20 Another object of my invention is to provide a connector device of such construction that when the plug part of a connector device or a vacuum tube is plugged into the socket part of said connector device, the hand of the person performing the plugging-in operation is prevented from coming in contact with the prongs of the device being 25 plugged in as same are making contact with live contacts in the socket.

Another object of my invention is to provide a 30 socket for a connector device of such construction that accidental contact with the prong-receiving elements shall be prevented when a plug is inserted or removed.

Another object of my invention is to provide a 35 socket for a connector device through which a multi-conductor cable may be passed in its entirety and having contact-element-accommodating wells so disposed therein that the conductors constituting the cable may be thereafter soldered to their respective terminals and the terminals disposed in the said wells with minimum labor.

40 Another object of my invention is to provide a socket for a connector device of the type described, the contact-element-accommodating wells being so constructed as to prevent rotation or displacement of the female contact elements carried therein should strain be exerted upon the cables connected thereto.

45 Another object of my invention is to provide a molded socket to receive and hold contact elements, said socket of Bakelite or the like having such configuration that the contact elements

carried therein are separated from each other by ample integral barriers of insulating material.

Another object of my invention is to provide a connector device or socket adapted to receive the prongs of a cathode ray tube tuning indicator or 5 the like, the socket being so constructed that the assembly may be mounted upon a panel or the like through the medium of clamping means encircling either the tube-base or the socket itself.

A still further and more specific object of my 10 invention is to provide a prong-receiving contact element of novel configuration, especially adapted for use in the molded socket heretofore referred to.

The foregoing objects and other objects ancillary thereto I prefer to accomplish by providing a molded socket, generally cylindrical, having in one end thereof an axially extending cable-receiving opening that merges into a larger opening in the other end into which the base of a tube 20 or of a male connector device may be inserted.

Intermediate the two openings, I provide a circular ledge. A plurality of main contact-receiving wells extend axially into the ledge to a distance short of the cable-receiving end of the 25 socket, the wells being circumferentially spaced around the cable-receiving opening and the open end of each well merging into a lateral niche, open at the top, that extends toward the base of the socket for a distance short of the bottom of 30 the main well associated therewith with the niches each having a side wall, the upper edge of which is spaced from the substantial plane of the circular ledge to permit a connector to extend transversely thereof below the level of the ledge 35 and to act as a lateral stop for a niche-disposed lug on a well-disposed contact.

Furthermore, the cable-receiving opening is provided with a plurality of wire-separating ribs that extend axially thereof for a distance short 40 of the ledge and of the small end of said opening.

Further, I provide a plurality of small protuberances on the inner surface of the larger opening in the socket for the purpose of holding in place a protective cover having openings therethrough corresponding in position to the contact-accommodating wells. The protective plate preferably is provided with a peripheral indexing bay into which a rib on the inner wall of the large opening extends for the purpose of preventing 50 the protective plate from being rotated and also to aid in alignment at time of assembly.

The novel features that I consider characteristic of my invention are set forth with particularity in the appended claims. The invention 55

itself, however, both as to its organization and its method of operation, together with additional objects and advantages thereof, will best be understood from the following description of certain specific embodiments when read in connection with the accompanying drawing, in which:

Fig. 1 is an exploded view in perspective of a socket and tube base assembly, the socket being shown in cross-section,

Fig. 2 is a top plan view of a wired socket, one of the contact elements being omitted in order that the relation between the main wells and the side-niches may be more clearly apparent,

Fig. 3 is a view in vertical cross-section of a connector device constructed according to my invention taken along a line corresponding to the line 3-3 in Fig. 2, looking in the direction of the arrow,

Fig. 4 is a side elevational view of an illustrative form of contact,

Fig. 4A is a plan view of the contact of Fig. 4 with a fragment of a wire connector shown as soldered thereto,

Fig. 5 is a side elevational view of a modified form of contact,

Fig. 5A is a plan view thereof,

Fig. 6 is a side elevational view of the preferred form of contact, and

Fig. 6A is a plan view thereof.

In all figures of the drawing, equivalent elements are similarly designated.

Referring now to Figs. 1, 2 and 3 of the drawing, a socket constructed according to my invention is constituted by a molded element 1 generally cylindrical in contour, having at one end an axial opening 3 just sufficient in diameter to accommodate a multi-conductor cable 5. The cable-receiving opening merges into a cylindrical opening 7 at the other end of the socket, having a diameter just sufficient to receive and accommodate the base 9 of a vacuum tube 11 or of a male connector device. The inner wall of the large opening is provided with a plurality of stepped circumferential ledges 13, 15 and 17, the ledge 13 nearest the tube-receiving opening affording stop-means for preventing the base of the tube or of the male connector from being pushed too far into the socket.

Looking into the socket from the tube-receiving end, the next ledge 15 serves as a support for a protective cover 19 of insulating material and it is spaced axially of the socket a very short distance from the ledge 17 nearest the cable-receiving end thereof.

Still looking into the socket from the large opening, it will be noted that the last mentioned ledge 17 is provided with a plurality of circumferentially disposed circular wells 21 separated, 60 each from the other, by walls 23 of the molding material.

The open end of each of the wells merges into a lateral niche 25 or side pocket that extends toward the cable-receiving end of the socket from a distance short of the plane in which lie the bottoms of the main wells 21. Each niche is separated from the open axial channel by the relatively short or notched wall 31 defining an end of the niche.

In wiring my improved socket, the cable is drawn through the small opening of the socket and is thereafter fanned out. To the free end of each of the conductors of the cable is affixed a contact element 27, semi-cylindrical in contour and provided at one end with a generally

radially projecting turned-down lug 29 or soldering tab. Between the tab and the wall of the contact element the end of the associated conductor may be passed and soldered in place, to extend substantially tangentially of the contact 5 as clearly shown in Figs. 1 and 4. The soldering operation may be performed while the contact elements are supported on the prongs of a jig (not shown) or in any other desired manner.

After the soldering operation, the cable is retracted, drawing the semi-cylindrical portion of each contact element within one of the main wells substantially until the connector abuts the notched side walls 31, each soldering tab being accommodated by the side pocket or niche into 15 which the open end of the main well merges. It will be observed that the lug 29 is axially of such length as to project downwardly into the niche 25 below the level of the upper edge surface of the side wall 31 when the contact 27 is housed in 20 the well 21.

It will be noted from an inspection of the drawing that the wall 31 of each side pocket nearest the central cable-receiving opening is cut down or notched a slight amount, thus permitting the insulation to extend to within a very short distance of the point of substantially tangential connection of a wire to its contact element.

The notches, recesses or cut-down walls thus formed in the sides of the niches, cooperating with the soldering tabs on the contact elements engaged behind side walls 31, effectively prevent the said elements from turning and becoming displaced when strain is exerted upon the cable. 35 It will be evident that axial pull on the cable in the axial channel of the housing is translated into direct tension on the connectors radial of the channel which due to the tangential engagement with the individual contacts exerts substantially axial torque only thereon and which is absorbed by engagement of the soldering lugs against the inner surface of the side wall 31 and by the relative stiffness of the conductor itself. The arrangement of contacts and contact lugs, 45 conductors, wells, niches and side walls is all such as to dispose the mounted or inserted elements not appreciably above the substantial level of the well-containing ledge 17 so as to be successfully concealed and held in place by cover plate 19 mounted on the ledge 15.

The cover plate is provided with a peripheral notch 33 or bay of sufficient depth to accommodate an axially extending protuberance 35 on the inner wall of the socket, the said protuberance 55 being disposed between the tube-base-supporting ledge 13 and the ledge 15 on which the cover plate rests. The notch and protuberance serve to index the holes in the cover plate with respect to the contact elements and to prevent it from turning.

The cover plate is held in place upon its ledge beneath a plurality of small protuberances 37 on the inner wall of the socket. By reason of its resilience, the cover plate may easily be snapped 65 in place.

In addition to its indexing or prong-guiding function, the cover plate also prevents the contact elements from displacement when the male connector is withdrawn.

It will be noted from an inspection of Figs. 1 and 2 of the drawing that the inner wall of the socket between the ledge into which the wells extend and the smaller cable-receiving opening is provided with a plurality of circumferentially 75

spaced ribs 39 that extend toward the axis of the socket. These ribs assist in maintaining the wires of the cable in proper alignment.

It is, of course, to be understood that I am not limited to the use of the specific contact element exemplified by Figs. 6 and 6A of the drawing, wherein the soldering tab is shown as being so bent down from one end thereof as to leave a notch 41. That form, however, is preferred.

10 As shown in Figs. 4 and 4A and 5 and 5A, the tab also may be formed by bending over and downward a small tongue extending directly from the edge of one end of the contact element.

Also, as exemplified by Figs. 5 and 5A of the drawing, the contact element may have a plurality of additional interior wiping edges 43 disposed axially thereof and formed by providing a slot in the wall thereof on the soldering tab side and turning inwardly the edges of the slot.

20 It will be apparent from the foregoing description of an embodiment of my invention that it is an improvement over similar devices which require the threading of the conductors through a plurality of separate openings individual thereto. 25 It should also be apparent that my improved connector may be manufactured and assembled with minimum labor and at minimum expense. In addition, in view of the fact that the contact elements are separated from each other by adequate insulation and are prevented from becoming displaced, my improved connector is quite well adapted to be utilized in situations where relatively high potentials exist among the wires constituting the cable.

30 Although I have chosen a preferred form of my connector device and several forms of the contact element itself for purposes of explanation, it is not to be inferred therefrom that I am limited to the exact forms disclosed. On the contrary, since numerous modifications of my invention will be apparent to those skilled in the art to which it pertains, my invention is to be limited only by the prior art and by the spirit of 35 the appended claims.

40 I claim as my invention:

1. A molded socket, generally cylindrical in contour, having in one end a connector-receiving opening, in the other end a cable-receiving opening, the said openings merging into each other through an intermediate channel having a diameter less than that of the first mentioned opening and greater than that of the second mentioned opening whereby a circumferential ledge, facing the first mentioned opening is defined, the ledge being provided with a plurality of contact element-receiving wells opening toward the large opening in the socket and, one side wall of each well being provided with a lateral niche 50 the bottom of which lies above the bottom of the accompanying well, and having the inner wall of each niche depressed to provide space for an insulated wire.

60 2. A molded socket having a large connector base-receiving opening in one end that merges into a relatively small cable-receiving opening at the other end, a circumferential ledge being disposed on the inner wall of the device, intermediate the said openings, the said ledge being provided with a plurality of circumferentially disposed wells opening toward the large opening, one side wall of each well being depressed to a depth short of the bottom thereof to form a side pocket, the side pockets being circumferentially spaced and the inner wall of each side

5 pocket being notched to provide space for the accommodation of an insulated wire.

3. The invention set forth in claim 2, additionally characterized in that the inner surface of the socket between the ledge and the cable-receiving opening is provided with a plurality of axially disposed ribs that function to assist in maintaining a plurality of conductors spaced apart when the socket is in use.

4. In combination, an insulating base provided 10 with a well, the opening of the well being cut away at one side to form a pocket, one side wall of the pocket being notched, a semi-cylindrical contact element one end of which has a turned down integral soldering tab so disposed in the 15 well that the tab is accommodated by the side pocket, and a conductor, one end of which is disposed between the tab and the contact element, the conductor lying in the notch in the 20 wall of the side pocket.

5. A molded socket having a central axial opening having an axis and containing a ledge substantially perpendicular to the axis of the opening, a plurality of wells disposed substantially in a ring in the ledge concentric to the central opening and each having an axis substantially parallel to the first mentioned axis, a cable end disposed in the opening and comprising a plurality of conductors fanned out at the end of the cable and terminating in the vicinity of 30 the ledge, each conductor end extending substantially radial of the opening, a plurality of substantially cylindrical contacts disposed in the respective wells and respectively coupled to a conductor end with the latter extending substantially tangentially thereof so that endwise cable pull with the contacts in the wells is converted into rotative torque on the contacts, and means to resist rotation of the contacts in the 35 wells.

6. A molded socket having a cord receiving axial opening and a ledge substantially perpendicular to the axis of the opening, a well disposed in the ledge to one side of the cord receiving opening and having an axis substantially parallel to that of the cord receiving opening, a 45 cable end disposed in the opening and the conductor thereof terminating in the vicinity of the ledge, the end of the conductor extending substantially radially to the axis of the opening, a 50 substantially cylindrical contact disposed in the well and coupled to the conductor end with the latter extending substantially tangentially thereof so that endwise cord pull with the contact in the well is converted into rotating torque on the contact and means to resist rotations of the contact in the well.

7. A molded socket having a cord receiving axial opening and a ledge substantially perpendicular to the axis of the opening, a well disposed in the ledge to one side of the cord receiving opening and having an axis substantially parallel to that of the cord receiving opening, a 60 niche communicating with the well in a line angularly divergent from a line between the cord receiving opening and the well, a cable end disposed in the opening and the conductor thereof terminating in the vicinity of the ledge in substantially axial alignment with said niche, the end of the conductor extending substantially radially to the axis of the opening, a semi-cylindrical contact disposed in the well, an anchoring lug extending generally radially of the contact connected to the conductor end and disposed in the niche with the conductor end extending sub- 70 75

stantially tangentially of the contact so that end-
wise cord pull with the contact in the well is con-
verted into rotating torque on the contact and
stop means integral with the socket to resist ro-
tation of the contact in the well by resisting
movement of the lug in the niche.

8. A molded socket having a cord receiving
axial opening and a ledge substantially perpen-
dicular to the axis of the opening, a well dis-
posed in the ledge to one side of the cord receiv-
ing opening and having an axis substantially
parallel to that of the cord receiving opening, a
niche communicating with the well in a line an-
gularly divergent from a line between the cord
receiving opening and the well, a wall defining
one surface of the niche and extending trans-
versely of a line between the cord receiving open-
ing and the niche, a cable end disposed in the

opening and the conductor thereof terminating
in the vicinity of the ledge in substantially axial
alignment with the said niche, the end of the
conductor thereof extending substantially ra-
dially to the axis of the opening transversely of
said wall, a semi-cylindrical contact disposed in
the wall, an anchoring lug extending generally
radially of the contact at a point not below the
level of the upper edge of the wall and having
an end disposed in the niche with the conductor
end extending substantially tangentially of the
contact so that endwise cord pull with the con-
tact in the well is converted into rotating torque
on the contact, and said wall comprising stop
means arranged for abutment by the lug to re-
sist torsional movement of the contact in the
well. 5 10 15

SAMUEL SUTTER.
